BOBBIN OR BRAIDING MACHINE

Emil Krenzler, Wuppertal-Barmen, Germany

Application August 22, 1932, Serial No. 629,935
In Germany December 18, 1931

10 Claims. (Cl. 96—12)

I have filed applications as follows: Germany Dec. 18, 1931 and England Jan. 6, 1932.

The invention relates to a bobbin or braiding machine with driving plates, which are rotated only as required and can be fixed in the resting places arranged in apertures of a track plate, and having notches or apertures of which the edges effect both the movement of the bobbin and also its guidance at the crossing places of the track. 10 In connection with machines of this kind it has already been proposed in the eighties of the previous century by Malhère (French Patent 155,703 of 1883) to provide the bobbin carriers with elongated hearts or stems of which both lateral surfaces were curved to an arc of the radius of the plate. In this case the notches in the plate, which were arranged symmetrically to the longitudinal and transverse centre lines of the plate, were of the same length as the stems of the 15 bobbin carriers and their edges were curved in exact correspondence with the lateral surfaces of the stems, so that the elongated stems fitted exactly over their full area in the notches of the plates. This arrangement resulted indeed in the 20 simplest manner in a faultless guiding of the bobbin carrier, but it was only possible because in Malhère's machine the plates were arranged not in a circle but in a straight line. The arrangement of the plates in a straight line is however not practicable because the distance of the 25 bobbin from the braiding point is subject to such great change that the alterations in the free lengths of the threads resulting therefrom cannot be compensated. In the practical construction 30 of the bobbin machine with driving plates (see for example German Patent 216,529 A. D. 1908 of Krenzler and the patents of addition thereto), the provision of the bobbin carriers with elongated stems in combination with the 35 arrangement of the plates in a circle, was therefore abandoned and bobbin carriers with circular stems were employed, while the notches in the plates were formed unsymmetrically in such a manner that their edges were only in part curved 40 to a circular arc of the radius of the plate and at one end on the other hand they were curved or angularly bent to a considerably smaller radius for forming an effective driving edge. The arrangement of the driving plates in a circle necessitates at the same time a shortening or blunting 45 of the points of the track plate lying on the outside of the machine and, above all, at the places where the bobbin carriers run from the crossing place of the track towards the outside. This necessitates the arrangement of separate guide-

pieces which are adjustable together with the coupling sleeves or clutches of the driving plates and have to guide the bobbin carriers without shock over the gaps which are present at the blunted points of the track plate. 5

At a later date the provision of the bobbin carriers with elongated stems of which the lateral surfaces were curved to a circular arc of the radius of the plate was again proposed. According to this later proposal (German Patent No. 439,426 A. D. 1924 of Eberle) the notches in the plates, similarly as in the case of the older proposal of Malhère, are of the same length as the stems of the bobbin carriers and their edges are curved in correspondence with the lateral surfaces of the stems. In order nevertheless to be able to arrange the plates in a circle, each driving plate is divided between its two notches into two sector-shaped halves which can be rotated relatively to one another through a certain angle about the centre of the plate. In this case there are arranged on the outside of the machine-circle expansion members, which are movable upwards and downwards with the driver couplings and, in the resting place of the plate, enter between the two halves of a plate and rotate these relatively to one another in such a manner that the edges of its notches are directly adjacent to the unshortened points of the track plate both on the inside and also on the outside of the machine. For coupling the divided driving plates with the driving wheels the coupling sleeves must then carry a separate driving or coupling member for each half of the plate. With this arrangement a guidance of the bobbin carrier without gaps is indeed obtained, but owing to the divided driving plates the machine is very complicated and expensive and is easily put out of order. 30 35

In the machine according to the invention in which the bobbin carriers also possess elongated stems or hearts, the lateral surfaces of which are curved to a circular arc of the radius of the plate, the arrangement of the plates in a circle is made possible with means which are considerably simpler. According to the invention, the plate notches which receive the stems of the bobbin carriers, similarly as in the case of the old Malhère machine in which the plates were arranged in a straight line, are arranged symmetrically to the longitudinal and transverse centre lines of the plates each of which forms a rigid whole. They differ however from the previous machines having bobbin carriers with elongated stems in that the notches are longer than the stems of the bobbin carriers and their 40 45 50 55

edges are curved in the form of an arc in such a manner that their end portions have the same radius of curvature as the side surfaces of the elongated stems. The notches are at the same time so arranged that the end portion of a notch which, when the driving plate is stationary, lies on the inside of the machine forms a direct continuation of the circular periphery of the adjacent plate and therefore a continuation of the edge of the aperture of the track plate which is in contact with it. Thus the edges of two adjacent plates, in the case of plates which are in the resting places, are contiguous on the inside of the machine to the point of the track plate while, on the other hand, on the outside of the machine, they are at some distance from one another, so that at this place the notches of two adjacent plates are spaced apart to some extent similarly as in the case in a bobbin machine having bobbin carriers with circular stems. Further, in accordance also with the invention the points of the track plate lying on the outside of the machine, at the places where the bobbins are moved from the crossing plate of the track towards the outside are blunted or shortened in the manner which has become known in the case of machines with circular stems, so that they do not project between the adjacent end edges of the notches in the plates. With the described arrangement and construction of the driver notches, the elongated stems of the bobbin carriers do indeed no longer fit closely over their entire lengths in the plate notches and a close fit to the edges of the notches only now takes place at the ends of these edges over about half the length of the lateral surfaces of the stems. This is, however, quite sufficient for the regular guidance and movement of the bobbin carrier. Owing to the fact that the elongated stems are tightly guided against the driver notches on both sides for about half of their length and, although in the resting places of the driving plates they have play in the notches and can therefore adjust themselves at will, they are nevertheless automatically correctly adjusted each time a driving plate is set in motion and adjusted with the point on that part of the track which belongs to the driving plate which is rotated at the time and they are then guided round freely by the plate. This action takes place not only on the movement of the bobbin carrier from the crossing point inwards, i. e. at the place where an uninterrupted guidance of the bobbin carrier is present, but also on the outside of the machine, that is to say where the guide is interrupted. At this place the bobbin carrier stems are positively guided by the edges of the notches in the plates until the point which is in front in the direction of movement has passed the blunted point of the track plate and the further guidance can then be undertaken by the aperture in the track plate.

As will be clear, the new machine is considerably simpler and cheaper than the known bobbin machines with elongated stems and plates arranged in a circle, since undivided rigid plates are employed. At the same time the new machine is also simpler than the known bobbin machines having bobbin carrier with circular stems, since, the guiding pieces, which are regulated with the coupling sleeves of the driving plates, necessary in these machines for bridging over the gaps in the bobbin carrier guidance on the outside of the machine are entirely dispensed with. It also possesses the advantage over these

machines that the arrested bobbins in the plate notches have only relatively little play. In addition the known advantage arising from the use of elongated stems is of course present, this is that wear is reduced owing to the enlargement of the sliding surfaces of the stems of the bobbin carriers. By means of the invention, therefore, owing to a happy combination of a number of quite simple features which are in part known and in part new, there is obtained a particularly advantageous form of construction of a single thread braiding or bobbin machine having bobbins with elongated stems and driving plates arranged in a circle. The essence of the invention, as a comparison with what has previously been proposed will show, resides in the recognition that the previous construction of the machine which operates with bobbin carriers having circular stems can be substantially maintained when bobbin carriers having elongated stems are employed, and that it is only necessary to make the notches in the driving plates completely symmetrical and to adapt them as far as possible to fit the shape of the elongated stems. The previous inventors who were concerned with the construction of a bobbin machine having driving plates arranged in a circle and bobbin carriers with elongated stems failed to recognize this.

The omission of the guiding pieces which are necessary in the known bobbin machines having bobbin carriers with circular stems for bridging over the gaps in the bobbin carrier guidance on the outside of the machine is a particular advantage in those bobbin machines in which not only the connection but also the disconnection of the couplings of the driving plates is positively effected, and for this purpose there are provided on the driving wheels cams for effecting the positive downward movement of the coupling sleeves or clutches which were moved upwards on being connected. In these machines the arrangement of the guide pieces occasions special difficulty. Either the guide pieces have to be so arranged that they are normally out of their operative position and only reach their operative position on the connection of a driver, which necessitates the connection of the guide-pieces with the coupling sleeves belonging to the adjacent plates by means of crossing arms. Or the guide pieces have to be mounted on separate swinging levers which are moved counter to the coupling sleeves. If it was not desired to include this complicated arrangement then it was necessary to arrange the guide pieces above the track plate, which causes difficulty in the arrangement of the disconnecting ring which is situated at this place. The complete elimination of the guide pieces in machine in which the coupling sleeves or clutches are positively connected and disconnected is therefore a very great simplification so that, by the combination of the new construction of the machine with the known positive regulation of the coupling sleeves, a very advantageous form of construction of a single thread bobbin or braiding machine is obtained.

The provision of the bobbin carriers with elongated stems naturally necessitates that the upper part and the lower part of the bobbin carrier are relatively rotatable, as the upper part which carries the bobbin and the thread guides needs to make no rotation during the movement of the bobbin carrier over the track. For this purpose the upper part has hitherto been revolubly mounted by means of a sleeve on a vertical pin on the upper foot disc of the bobbin carrier, for

example with the interposition of a ball bearing. According to the present invention the same end is obtained in a considerably simpler manner by revolubly arranging the elongated stem between the two foot plates of the bobbin carrier on a pin which preferably forms one piece with these foot plates. In this case the elongated stem consists of two plates lying one above the other which are riveted or welded together. These plates are provided with slots or apertures which are open to opposite sides for the passage of the pin connecting the foot plates so that they can be inserted from opposite sides between the foot plates and then connected together. In so far as the connection is effected by means of rivets, the foot plates of the bobbin carrier are provided at the places where the rivets are located with holes for the passage of the rivets or riveting tools. The revoluble arrangement of the elongated stem on the foot of the bobbin carrier is not only simpler than the revoluble mounting on the upper part of the bobbin carrier on the foot but has, above all, the advantage that the known form of bobbin carrier with a circular stem, of which the foot consists of two discs connected by a pin which forms the circular stem can be constructed to form a bobbin carrier with an elongated stem by simply fitting two plates which form the elongated stem. The pattern of the known bobbin carrier with circular stem can thus still be used, so that the bobbin carrier can be wrought with the dies already at hand and, in particular, the same upper parts of the bobbin carrier can be used as in the case of bobbin carriers with the usual circular stems.

A constructional embodiment of the invention is illustrated by way of example in the accompanying drawing, in which

Fig. 1 is a plan of a part of a bobbin or braiding machine in which, for the sake of simplicity, the elongated stems of the bobbin carriers are illustrated as solid bodies.

Fig. 2 is a radial section through the machine plate on the line A—A of Fig. 1, with a side elevation of a plate and the pertaining driving parts,

Fig. 3 is a horizontal section on the line B—B of Fig. 2,

Fig. 4 a longitudinal section through the foot of a bobbin carrier,

Fig. 5 a side view, at right angles to Fig. 4, of the foot of the bobbin carrier with a section through the elongated stem, and

Fig. 6 a plan of the foot of the bobbin carrier with the upper foot disc cut away.

Referring to the drawing, 1 is the base plate, 2 the track plate of the machine, 3 are the driving plates which are arranged in a circle in apertures in the track plate and are revolubly held by counter-sunk nuts 4 on the upper ends of the pillars 5 fixed to the base plate 1. On the pillars 5 at their bottom ends are mounted the continuously rotating driving wheels 6, on the upwardly prolonged bosses of which are mounted upwardly and downwardly movable clutches 7 which rotate with the driving wheels. The clutches 7 carry on their upper side two driving lugs 8 with which there co-act as counter-coupling members, two radial lever arms 10 provided at the lower end of the boss 9 of the plate. The clutches are usually located in their lower end position in which their lugs 8 are free from the lever arms 10. If a plate is to be rotated the clutch 7 is raised so that the lugs 8 engage the two arms 10 on the boss of the driving plate and so drive the plate.

If the driver is to be again arrested then the clutch 7 is lowered into its lower end position. The upward and downward movement of the clutches 7 is effected with the aid of forks 11 which engage in annular grooves in the clutches and of which each is mounted on a bar 12 which is guided in the base plate 1 and track plate 2. These bars can be positively moved upwards through the agency of an angle lever, which is not illustrated, mounted on the lower side of the base plate 1 by means of a connecting rod to the pattern gear. Their downward movement is also positively effected, namely by a cam 13 provided on the lower side of the driving wheel 6 which co-acts with an arm 14 fixed to the rod 12. The regulating fork 11 for the clutch carries at its upper side a second fork 15 which co-acts with the arms 10 on the driver boss 9, in order to fix the disconnected driver plate in the position of rest. The two arms of the fork 15, abut when the clutch 7 is lowered, against the two arms 10 of the driver boss and thus secure this against rotation in both directions. If the clutch is connected the fork 15 is then simultaneously raised above the arms 10 so that it releases the driving plate for its rotation.

The driving plates 3 are each provided at their edges with two notches 16 which are diametrically opposite and which are employed, on the one hand, for driving the bobbin carrier and, on the other hand, for guiding it at the crossing places of the track. In the position of rest of the drivers 3 two notches 16 of two adjacent plates are always opposite one another and thus arrest the bobbin carrier at the crossing places of the track. The two notches 16 of any one plate are arranged symmetrically both with respect to the longitudinal centre line x and also to the transverse centre line y (see the left-hand side of Fig. 1) of the plate, so that the outline of the plates is quite symmetrical. The edges of the notches are curved to a circular arc and in such a manner that each edge consists of two arcs a and b forming the end portions of the notch (see the left-hand side of Fig. 1) and a likewise curved line which connects these arcs a and b in the centre of the notch, in some cases this curve may be replaced by a straight line. The two similar arcs a and b are curved to a radius which is equal to the radius c of the circular part of the periphery of the plate. The length and arrangement of the notches 16 in the driving plates 3 is designed, as may be seen from Fig. 1, in such a manner that, when the plates are stationary at any time, the end edges a or b of the notches of two neighbouring plates which lie on the inside of the circle of plates are contiguous to the inner point of the track plate which is adjacent to them. The parts a or b of the edges of the notches which lie on the inside of the machine, i. e. at the top in Fig. 1, therefore form, owing to the fact that they are curved to the radius of the plate, a direct continuation of the circular peripheral edge of the adjacent plate or the guiding edge of the track plate 2 which adjoins the same. At the outside of the machine, that is at the bottom of Fig. 1, the ends of the adjacent notches 16 of the plates are at some distance apart, so that at this place the notches of the neighbouring plates are separated to a slight extent. At all places where the bobbin carrier has to be moved from the crossing place of the track or from the arresting place towards the outside, the outer points 17 of the track plate are shortened or blunted so that they do not engage

between the notches of the adjacent plates. The remaining points of the track plate, namely both the inner points 18 and also the outer points 17a, are on the contrary unshortened.

5 The bobbin carriers for the machine have elongated stems 19 of lens-shape or double angled cross-section. These stems are of a slightly less length than the length of the notches 16 in the driving plates 3. Their two lateral surfaces are 10 curved to a single arc, the radius d of which corresponds to the radius c of the driving plate. Thus their lateral surfaces fit the arcs a and b of the notches in the driving plates, in such a manner that each lateral surface of a bobbin 15 stem is in close contact for about half its length with one end portion of the edges of the notches in the driving plates and can be closely guided for about half the length of the stem as may be seen from Fig. 1.

20 In Fig. 1 the greater part of the driving plates 3 is illustrated in the position of rest. The bobbin carriers located between the stationary plates are thus arrested at the crossing places of the track. Since the notches 16 in the plates are 25 somewhat larger than the elongated stems 19, the bobbin carriers, in their position of rest, have some play in the notches. This however is without effect on the guidance of the bobbin carriers on their further movement. For, as soon as a 30 driving plate is set in motion, the stems of the two bobbin carriers to be moved by this plate abut with both lateral surfaces for about half the length of these surfaces both against the edges of the notches of the rotating plate and 35 also against the edges of the notches of the two adjacent stationary plates. Therefore, as illustrated in full lines on the right hand side of Fig. 1, they are so adjusted that the points which are front in the direction of motion are directed onto 40 the part of the track belonging to the rotating plate and are thus positively guided into the desired part of the track. The bobbin carrier which moves to the inside of the machine has moreover an uninterrupted guidance at the edge of the notch 45 in the stationary plate. At the outside of the machine this guidance is indeed lacking. At this place, however, owing to the fact that the rear half in the direction of motion of its elongated stem 19 is in close contact on both sides with the 50 notches in the driving plates the bobbin carrier is positively guided by the plates themselves into the correct position, until its point which is in front in the direction of motion has passed the shortened point 17 of the track plate and the 55 bobbin carrier can now be properly guided by the aperture in the track plate. (See the positions illustrated at the right-hand side of Fig. 1 in full lines as well as those indicated in dotted lines). Special guide pieces for bridging over 60 the gaps present on the outside of the machine between the edges of the notches of the plates and the edges of the apertures of the track plate are therefore not necessary, on the contrary the guidance of the bobbin is now exclusively effected by the edges of the drivers and the edges 65 of the apertures in the track plate. The points of the elongated stems can preferably be slightly rounded off. This however is not necessary.

70 The bobbin carriers with elongated stems employed in the machine are so constructed that the carriers are able to rotate with their feet in the elongated stems. For this purpose the feet of the bobbin carrier, in accordance with Fig. 4-6, consists of two foot discs 20 and 21 and a cylindrical pin 22 which combines these and is

formed in one piece with the two discs 20 and 21. Between the two foot discs there are arranged one above the other two plates 23, 24, the similar outlines of which correspond to the desired outline of the elongated stem 19. The two plates 23 and 24 each possess an aperture or slot 25, 26 respectively, which is open to one side, and is bounded on the inner end by circular arc. They are inserted between the two foot discs from opposite sides with the open end of the slot in front and each of them is thus inserted with its aperture around the pin 22. The two plates 23, 24 are then fixed together in superimposed position, preferably by means of two rivets 27, which are introduced in corresponding 10 holes in the two plates. In order to insert the shanks of the rivets and to be able to upset their ends, the two foot discs 20 and 21 are provided with holes 28 which coincide with the holes in the plates 23, 24 and are of such a size as to 20 allow the passage both of the shanks of the rivets and also of the riveting tools. The thickness of the two plates 23, 24 and the width of their apertures 25, 26 is so selected that the plates are guided on the foot of the bobbin without 25 play but are able to turn easily about the pin 22. Since the open ends of the two apertures 25, 26 in the plates 23 and 24 are located in the finished bobbin-carrier foot in opposite sides of the elongated stem, there is obtained, in spite 30 of the presence of these apertures on each side, a sliding surface which extends over the entire length of the stem. The holes in the foot discs of the bobbin carrier can also advantageously be used for lubricating the surfaces of the elongated 35 stem which slide on the foot discs 20, 21.

The upper foot disc 20 carries on its upper side the sleeve 29, which also forms one piece with the foot, for the insertion of the end of the spindle of the upper part 30 of the bobbin carrier. 40 The sleeve 29 can in some cases be replaced by a pin over which the upper part of the bobbin carrier is placed.

Modifications of the examples illustrated as 45 well as other forms of construction are of course included within the invention. Thus for example the machine may be a right-handed and left-handed machine, that is to say it may be so arranged that each driver can be rotated clockwise or anti-clockwise as desired. In a machine of this 50 kind the new construction of the driving plates and the arrangements of elongated stems on the bobbin carriers is considerably more advantageous than the known arrangement of circular stems in such machine since the bobbin carriers 55 can be faultlessly guided and driven in both directions of rotation. In the construction as a right-handed and a left-handed machine the outer track plate points 17 and 17a are all shortened 60 from the track crossing to the outside can then take place at all places. Instead of the clutches 7 being positively moved in both directions the arrangement may also be such that the clutches 65 are moved in the direction of disconnection by power conserving means, for example springs. In this case its arrangement may be the reverse of that illustrated, that is to say it may be such that the clutches are located in the disconnected 70 condition in an upper end position and are moved downwards for the purpose of connection. The fixing of the driving plates 3 in the position of rest can then be effected, as known, by lugs provided on the regulating forks of the clutches 7 75

which engage in recesses on the under side of the driving plate.

The bobbin carrier illustrated can also be modified in that the two plates 23, 24 which form the 5 elongated stem 19, instead of being connected together by rivets, can be connected by point welding. Or, the fixed connection of the two plates can be dispensed with, since they are secured against becoming loose from the foot of the 10 bobbin carrier by the guidance on the foot discs and by the guidance on the edges of the apertures in the driving plate and the track plate. In some cases the elongated stem may also be made in one piece. In this case it can consist of 15 a perforated plate which is inserted axially in the pin in the foot of the bobbin carrier in which case the foot of the bobbin carrier must of course be in two parts. Or the one-part plate which forms the stem can, by means of an aperture which receives the pin and is open on one side, be pushed sideways between the foot plates. In this case also, as in the case of the arrangement of the plates which are not connected together, there is 20 the advantage of easy interchangeability of the elongated stem.

In combination with the new machine in some cases also the known bobbin carriers with elongated stems in which the upper part is revolvably mounted on the foot of the bobbin carrier can be 25 employed.

Having now particularly described and ascertained the nature of my said invention and in what manner the same is to be performed, I declare that what I claim is:—

35 1. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having the peripheries of its end portions forming an arc of equal radius to the radii of the arcuate portions of said openings, the centers of the arcuate end portions of each notch being spaced longitudinally of the plate and the notch having a peripheral portion connecting the arcuate end portions thereof, and means to actuate said plates; in combination with bobbin carriers having stems of cylindrically lenticular shape with their major diameter less than the length of a notch and their sides being segments of cylinders of equal radius to the radii of the end portions of the notches.

60 2. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having the peripheries of its end portions forming an arc of equal radius to the radii of the arcuate portions of said openings, the centers of the arcuate end portions of each notch being spaced longitudinally of the plate and the notch having a peripheral portion connecting the arcuate end

portions thereof, and means to actuate said plates; in combination with bobbin carriers having stems of cylindrically lenticular shape with their major diameter less than the length of a notch and their sides being segments of cylinders of equal radius to the radii of the end portions of the notches, each stem being revolvable on its carrier with the axis of revolution coinciding with the axis of the carrier.

65 3. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having the peripheries of its end portions forming an arc of equal radius to the radii of the arcuate portions of said openings, the centers of the arcuate end portions of each notch being spaced longitudinally of the plate and the notch having a peripheral portion connecting the arcuate end portions thereof, said notches being symmetrically arranged with respect to the longitudinal and transverse axes of the respective plates, and means to actuate said plates; in combination with bobbin carriers having stems of cylindrically lenticular shape with their major diameter less than the length of a notch and their sides being segments of cylinders of equal radius to the radii of the end portions of the notches.

70 4. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having the peripheries of its end portions forming an arc of equal radius to the radii of the arcuate portions of said openings, the centers of the arcuate end portions of each notch being spaced longitudinally of the plate and the notch having a peripheral portion connecting the arcuate end portions thereof, said notches being symmetrically arranged with respect to the longitudinal and transverse axes of the respective plates, and means to actuate said plates; in combination with bobbin carriers having stems of cylindrically lenticular shape with their major diameter less than the length of a notch and their sides being segments of cylinders of equal radius to the radii of the end portions of the notches, each stem being revolvable on its carrier with the axis of revolution coinciding with the axis of the carrier.

75 5. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having

the peripheries of its end portions forming an arc of equal radius to the radii of the arcuate portions of said openings, the centers of the arcuate end portions of each notch being spaced longitudinally of the plate and the notch having a peripheral portion connecting the arcuate end portions thereof, said notches being symmetrically arranged with respect to the longitudinal and transverse axes of the respective plates, a constantly revolving drive member for each plate but normally free therefrom, a clutch device adapted for clutching operation from the pattern gear of the machine and arranged to clutch the respective plate to its drive member, means on each drive member unclutching its clutch upon completion of an operative movement of its plate, and means associated with each clutch and holding its plate against rotation between operative movement thereof; in combination with bobbin carriers having stems of cylindrically lenticular shape with their major diameter less than the length of a notch and their sides being segments of cylinders of equal radius to the radii of the end portions of the notches.

6. In a bobbin or braiding machine for bobbin carriers having stems elongated diametrically of the carrier, a track plate having a circular series of intercommunicating openings adapted to receive driving plates, the inner and outer portions of the periphery of each opening being concentric circular arcs, driving plates each held in a respective opening and each having convex ends adapted to fit the arcuate portions of its opening and each having concave sides forming notches for the bobbin carrier stems, each notch having the peripheries of its end portions forming an arc of equal radius to the radii of the arcuate portions of said openings, the centers of the arcuate end portions of each notch being spaced longitudinally of the plate and the notch having a peripheral portion connecting the arcuate end portions thereof, said notches being symmetrically arranged with respect to the longitudinal and transverse axes of the respective plates, a constantly revolving drive member for each plate but normally free therefrom, a clutch device adapted for clutching operation from the pattern gear of the machine and arranged to clutch the respective plate to its drive member, means on each drive member unclutching its clutch upon completion of an operative movement of its plate, and means associated with each clutch and holding its plate against rotation between operative movement thereof; in combination with bobbin carriers having stems of cylindrically lenticular

shape with their major diameter less than the length of a notch and their sides being segments of cylinders of equal radius to the radii of the end portions of the notches, each stem being revolvable on its carrier with the axis of revolution coinciding with the axis of the carrier.

7. A bobbin carrier for braiding machines of the class described comprising a stem, spaced discs on the lower part of the stem, said stem forming a journal between said discs, and a lenticular member mounted on said journal for engagement by the bobbin moving member of the machine, the said lenticular member as a whole having unlimited rotatable movement about said journal.

8. A bobbin carrier for braiding machines of the class described comprising a stem, spaced discs on the lower part of the stem, said stem forming a journal between said discs, a lenticular member rotatably mounted on said journal for engagement by the bobbin moving member of the machine, said lenticular member having a slot opening through one side to permit engagement of said member on said journal, and means to secure said member on said journal.

9. A bobbin carrier for braiding machines of the class described comprising a stem, spaced discs on the lower part of the stem, said stem forming a journal between said discs, a lenticular member rotatably mounted on said journal for engagement by the bobbin moving member of the machine, said lenticular member consisting of a pair of lenticular plates each having a slot opening through one side to permit engagement of the plate on the journal, said plates being arranged on the journal with the plate openings on opposite sides of said member, and means to secure said plates together.

10. A bobbin carrier for braiding machines of the class described comprising a stem, spaced discs on the lower part of the stem, said stem forming a journal between said discs, a lenticular member rotatably mounted on said journal for engagement by the bobbin moving member of the machine, said lenticular member consisting of a pair of lenticular plates each having a slot opening through one side to permit engagement of the plate on the journal, said plates being arranged on the journal with the plate openings on opposite sides of said member, rivets extending through said plates and securing them together, said discs having openings therein for insertion of said rivets in the plates.

EMIL KRENZLER.
